UNITED STATES PATENT OFFICE.

FRANK TILFORD, OF NEW YORK, N. Y.

DESIGN FOR A CANISTER.

41,239.

Specification for Design.

Patented Mar. 14, 1911.

Application filed August 4, 1910. Serial No. 575,576. Term of patent 7 years.

To all whom it may concern:

Be it known that I, FRANK TILFORD, a citizen of the United States, residing at New York city, county of New York, and State of New York, have invented a new, original, and ornamental Design for a Canister, as shown.

The design is illustrated in the accompanying drawing, in which the figure as shown illustrates a perspective view thereof.

I claim:

The ornamental design for a canister, as shown.

FRANK TILFORD.

Witnesses:

JAMES W. BUCHNER,
JOHN R. AGNEW.

Copies of this design may be obtained for five cents each, by addressing the "Commissioner of Patents, Washington, D. C."
